[57] CLAIM

The ornamental design for a collapsible copy holder stand, as shown and described.

DESCRIPTION

FIG. 1 is a top plan view of a collapsible copy holder stand showing my new design;

FIG. 2 is a side elevational view, the opposite side being a mirror image thereof;

FIG. 3 is a bottom plan view;

FIG. 4 is a rear elevational view;

FIG. 5 is a front elevational view;

FIG. 6 is a side elevational view of the article with the document holding member in an extended position, the opposite side being a mirror image;

FIG. 7 is a front elevational view of the article in an extended position; and

FIG. 8 is a perspective view thereof.
